UNITED STATES PATENT OFFICE.

DAVID ZISSELER, OF WETZLAR, PRUSSIA, GERMANY.

MACHINE FOR MAKING CEMENT TUBES.

SPECIFICATION forming part of Letters Patent No. 427,388, dated May 6, 1890.

Application filed November 7, 1887. Serial No. 254,531. (No model.) Patented in Germany July 22, 1887, No. 40,173.

To all whom it may concern:

Be it known that I, DAVID ZISSELER, of Wetzlar, in the Kingdom of Prussia and German Empire, have invented a new and useful Improved Machine for Producing Cement Tubes with Thin Walls, whereby the cement is deposited on wire-gauze, (no patents being obtained by me anywhere for this invention, save in Germany, No. 40,173, dated July 10 22, 1887,) of which the following is a specification, reference being had therein to the accompanying drawings.

My invention relates to the construction of thin-walled cement tubes with wire-gauze laid in, so as to facilitate and render practicable the manufacture of such tubes.

Figure 1 shows a front view of the machine used to make tubes with gauze. Fig. 2 shows a side view. Fig. 3 shows the connection of the two ends of the cylinder *a*, on which the cement for the tubes to be made is carried, in front view, Fig. 4 being an end view of same. Fig. 5 shows the cog-wheel of the drum on which the wire-netting is wound in side view, and Fig. 6 shows a section thereof. Fig. 7 represents a section of the disk, which is fastened at both ends of the cylinder *a*, which disk serves to limit the length and breadth of the layer of cement carried on the cylinder *a*. Fig. 8 is the front view of this disk. Fig. 9 shows the mode of attachment of a strip of zinc *G* by the spring *H*, which strip of zinc is used in setting a socket on the cement tube. Fig. 10 shows the arrangement of a second disk *D* in section, which also serves for setting a socket on the cement tube. Fig. 11 shows a cross-section of a complete cement tube. Fig. 12 depicts the mode of attachment of the wire-netting on the cylinder by means of a rail *w* and a clamp *v*.

This locking apparatus consists of two wedge-shaped metal or wood laths *b b*, fitted to the long sides of the sheet of zinc, and each having two screws or rivet-bolts *c c*, which serve to receive the connecting plates *d d*, Fig. 3, which are fitted on a third lath *b'*, also of wedge shape.

Three wedge-laths *b b' b* serve to lock the cylinder and have the advantage that they can be opened or closed in a moment by a handle.

Upon each of the two ends of the cylinder *a* thus formed a cast-iron disk *e'*, provided with a central rectangular aperture *f* and a projecting bordering *e*, is set, Figs. 7 and 8. 55 This projecting bordering gives the thickness of the wall of the cement tube to be made. Through the rectangular apertures *f* in the two disks *e'* a rectangular beam *g* is placed, Fig. 1, near the ends of which the disks *e'* are 60 immovably wedged by wedges *h*. The cylinder thus formed, the external diameter of which corresponds to the internal diameter of the cement tube to be formed, is now placed on the machine (shown in Figs. 1 and 65 2) in such a way that the two ends of the beam *g* are caught by fork-shaped carriers *i*, the shafts *k k* of which rest in the bearings *l* of the machine-frame *m*.

On the carriers *i i* adjusting-screws *n n* are 70 fitted, which go through the beam *g* and hold the latter firm, so that the cylinder *a* is set in rotation by turning the crank *o* by means of the spirals *p* and the toothed wheel *q*, Fig. 1, fitted onto the shaft *k*. At the back part of 75 the machine-frame *m* a shaft *r* is fitted, upon which the wire-gauze *s*, to be laid in the cement tubes, is rolled. Upon the shaft *r* there is also another toothed disk *r'*, on the nave of which a pulley *x* runs loosely, and is 80 held by a pawl, which gears with the toothed disk.

The aforesaid wire-gauze *s* is carried over a roller *u*, resting upon two side cheeks *t t* of the machine-frame and the end of the gauze 85 *s* by means of clamps *v*, Figs. 7 and 8, and by means of a rail *w*, extending over the entire length of the cylinder *a*, Fig. 12, is screwed on tight to the two end disks *e* of the cylinder *a*. 90

The process of manufacture of the cement tubes with wire-gauze laid in is as follows: In the first place the inner cement wall is formed, for which purpose the cement is placed on the cylinder *a* to the extent of half the thickness 95 of the wall, and the cylinder is then slowly turned by means of the crank *o*, spirals *p*, and toothed wheel *q*. The wire-gauze *s* will then lay itself firmly on the layer of cement, and the weight *y*, which runs over the pulley *x*, 100 gives the wire-gauze the requisite tension. If the weight *y* is raised up as high as the

pulley x , it will be let down again by releasing the catch. When the catch is recaptured, the tension of the wire-gauze recommences. By means of the crank z the wire-gauze is drawn up onto the shaft r . The inner cement wall being now formed, the gauze is cut off, the two ends are fastened together, the clamps v are released, and the lath w is taken off. To form the outer tube-wall, a second layer of cement is now laid on of such thickness that the layer of cement reaches the same height as the border disk e . The process above described is then repeated. In order that during the revolution of the cylinder the cement does not fall off by shaking, an endless cloth B , running over three rollers a' , is arranged. The two upper rollers a' rest in adjustable bearings C and the lower roller a' rolls freely over the cloth B . By the weight of the latter roller the cloth is pressed between the rollers onto the layer of cement, and thus prevents the stuff from falling off. If, now, a socket is to be made on the tube before placing the cylinder a in the machine, the corresponding larger socket-disk D , Figs. 9 and 10, and another ring D^2 are pressed, by means of a wedge E , against the disk e' , which rests on the beam g . Now a leather strip of suitable thickness F , two centimeters wide, is laid around the disk e' , and upon this again is laid a strip of zinc G , held together by springs H . The laying of the cement layer to half the thickness of the wall, the winding of the wire-gauze, and the placing of the outer cement layer are performed in the already-described way also when making sockets. If it is desired to make tubes of greater solidity, and for that purpose to put in more layers of wire-gauze, the gauze is not cut off until after the second or third revolution of the cylinder, (according to the number of

layers desired,) and then the outer cement layer is put on.

What I claim, and desire to secure by Letters Patent of the United States, is—

45

1. In combination with the roller, the independent movable disks e' , having bearing-surfaces for the roller, and having flanges e to afford a bearing for the cement.

2. In combination with the roller, the end disks having clamps v for the wire-gauze, substantially as described.

3. In combination, the roller a , the end disks e , having bearing-surfaces for supporting said roller, the beam g , for supporting the disks, the shafts k , provided with clamps for engaging the beam, and means for revolving the shaft k , substantially as described.

4. In combination, the roller, the end disks e for said roller, and the supplemental end disks D , having a bearing for the cement and being of larger diameter than the disks e , substantially as described.

5. In combination, the roller a , the end disks e , the supplemental disks D of larger diameter, and the strip G , with clamp to afford a bearing for the cement, substantially as described.

6. In combination, the roller for receiving the cement, means for supporting and revolving the same, and means for preventing the cement from falling therefrom during its revolution, consisting of the tension-apron B , passing over suitable rollers and beneath the roller, substantially as described.

75

In witness whereof I have hereunto set my hand in presence of two witnesses.

DAVID ZISSELER.
